UNITED STATES PATENT OFFICE.

FRANCIS I. MAULE, OF PHILADELPHIA, PENNSYLVANIA.

PIPE-VISE FOR BENCH-VISES.

SPECIFICATION forming part of Letters Patent No. 226,410, dated April 13, 1880.

Application filed January 19, 1880.

To all whom it may concern:

Be it known that I, FRANCIS I. MAULE, of Philadelphia, Pennsylvania, have invented a new and useful Pipe-Vise for Bench-Vises, of 5 which the following is a specification.

This invention relates to that class of vises known as "pipe-vises," for securely holding wrought-iron pipes while being cut and threaded.

10 The object of my invention is to construct a vise that will hold pipe and bind it securely while the workman is manipulating it.

It consists of a box or frame, to the end of which frame a pair of V-shaped jaws are rigidly secured. Between these jaws projects a 15 loop or hook, which is fitted to slide within the above-mentioned frame, and by means of a screw working in the opposite end of the hook the hook is drawn toward the fixed jaws 20 and the pipe securely held. This pipe-vise is constructed to be easily clamped in the ordinary bench-vise.

In the drawings, Figure 1 is a section through the case or box, showing the internal construction of the working parts. Fig. 2 is an edge view, showing flange for bolting to angle-plate on bench. Fig. 3 is a plan of the top of the vise. Fig. 4 is a side elevation, showing the operation of the jaws on a section of pipe.

30 Fig. 5 shows another form of movable jaw.

The outer box or case, A, is made in one or more pieces of cast or wrought iron, having the stationary gripping jaws D firmly riveted to it.

35 B is a movable jaw projecting beyond the end of the box A. It is connected with and forms a part of the sliding cross-bar N within the box. This cross-bar is threaded to fit the

screw C, which has a collar, c², and a cross-bar lever, c'. Into the top of the movable jaw 40 steel gripping-jaws E are fitted.

The upper and lower jaws, E D, are of steel, serrated, to hold the pipe more securely.

K is a removable lid, which is bolted to the box after the jaw B is in place. The jaw B is 45 made somewhat in the shape of a hook, open at one side, thus permitting the pipe to be placed in position from the side of the vise.

In my invention the pipe can be gripped at any desired point. The interior sides of the 50 box guide the movable jaw B, as it advances or recedes, by the turning of the screw C.

In Fig. 5 I show a modified form of the movable jaw B for extra heavy work. In Figs. 2 and 3 is shown a rib, a', cast or bolted to the 55 under side of the casing A, by means of which the vise can be held in the jaws of an ordinary bench-vise; or it may be attached to suitable angle-plates, and thus held firmly to the bench while being used.

60

I claim—

1. The combination of the hollow box A, suitable for clamping in vise-jaws, the fixed jaws D at one end of the box, the sliding jaw B, the threaded cross-bar N, sliding within the 65 box, the screw C, and lever c', operating substantially as described.

2. The combination of the box or frame A, the fixed jaws D at one end of the box, a sliding hooked jaw, B, open at one side, and the 70 threaded sliding cross-bar N, operated by the screw C, as herein described.

FRANCIS I. MAULE.
